UNITED STATES PATENT OFFICE

PHILIPP BLASCHKE, OF FISCHAMEND, AUSTRIA

SWITCH DEVICE FOR AUTOMATIC OIL-PRESSURE CONTROL AND SIGNALING APPARATUS

Application filed August 17, 1927, Serial No. 213,509, and in Austria April 10, 1926.

This invention relates to an: Automatic oil pressure control and signaling apparatus.

The known oil pressure lubricating devices of the type to which my invention relates are commonly provided with a contact part governed by the excess pressure in the oil pipes for switching in a warning signal in case of the pressure lubrication of the motor failing. With acoustic signals especially it is necessary to close the circuit of the controlling apparatus when starting and stopping the motor. If the closing of the current circuit is omitted when starting the motor, the apparatus though functioning does not emit signals.

The present invention consists therein that a second contact piece is inserted in these plants and connected in series to the contact piece mentioned above. This second contact is governed by the partial vacuum of the suction pipe of the motor and is placed in the signal series circuit, thus automatically switching in or out the control apparatus, when starting or stopping the motor.

The illustration shows an example of the object of this invention. In the Figs. 1, 2, 3 the apparatus is represented in section in the various working positions, Fig. 1 with the motor stopped, Fig. 2 with the motor running and the pressure lubrication functioning while Fig. 3 illustrates the working of the apparatus with the motor running within effective pressure lubrication.

A cylinder 2 provided with a piston 3 is inserted into the oil pipe 1. A pressure spring 4 is constantly endeavoring to move the cylinder to the position illustrated in Fig. 1. The head 5 of the piston rod may cooperate with one end of a contact spring 6 which is fastened to but insulated from the cylinder 2 by means of a plate 7. This plate 7 carries the contact piece 8, which is so designed as to come into electric contact with the other end 9 of the spring 6, and is connected to the usual signal line 10. An arm 11 provided on cylinder 2, which is connected to the earth, carries a second cylinder 12, which is connected by pipe 13 to the suction line of the motor. A spring 14 is constantly trying to lift piston 15 of the last mentioned

cylinder (Fig. 1) whereby the head 16 of the piston rod is made to act on the end 9 of the spring 6 and the contact between that part and the contact piece 8 is interrupted.

The position characterized by Fig. 1 corresponds to the conditions of the motor when stopped, as the piston 3 owing to the want of pressure in the oil pipe line 1 has reached its lowest position, while piston 15 owing to the absence of a suction effect of the motor is lifted and thereby interrupts the signal line.

When the working motor is acting and effective oil pressure exists in the system the piston 3 is placed in its upper position (Fig. 2) while the piston 15 is drawn back to its lowest position by the suction effect of the motor. Thereby the contact between head 5 and spring 6 is interrupted while the contact between the part 9 of the latter and the contact piece 8 is closed. As long as the oil pressure is maintained the circuit is broken and no signal can be given.

In case of the oil pressure lubrication failing while the motor is running, the piston 3 descends under the pressure of spring 4 (Fig. 3) whereupon without any change taking place in respect to the contact 8, 9, the contacts 5, 6 are closed and the signal is actuated until either the motor is stopped or the fault of the oil pressure line is rectified. The contact 8, 9 which is always closed as long as the motor is running, is bound to be automatically interrupted when stopping the latter.

In the place of the piston 15 a membrane or a valve may be employed.

I claim:

In a circuit closer for an alarm circuit, of a motor system having pressure lubrication, a cylinder, a piston therein movable in one direction under pressure and in the reverse direction upon the absence of pressure, primary and secondary contacts arranged in series, a contact carried by the aforesaid piston to engage the primary contact on the movement of the piston in the second-named direction, a tertiary contact adapted to be automatically engaged by the secondary contact when said secondary contact is unrestrained from action, a second cylinder, a pis-

ton in said cylinder carrying an insulated contact for engagement with the secondary contact, said piston being automatically movable in one direction to shift the secondary contact out of engagement with the tertiary contact and being movable by suction in the reverse direction to permit said secondary contact to engage said tertiary contact, a current supply conductor connected to said tertiary contact, and a common ground connection for said cylinders.

In testimony whereof I affix my signature.
PHILIPP BLASCHKE.
